US0D1023793S

(12) **United States Design Patent** (10) **Patent No.:** **US D1,023,793 S**
(45) **Date of Patent:** **** Apr. 23, 2024**

(54) **WATCH**

(71) Applicants: **ZEPP INC.**, California, CA (US);
ANHUI HUAMI INFORMATION TECHNOLOGY CO., LTD., Hefei (CN)

(72) Inventors: **Martin Julian Luu**, Cupertino, CA (US); **Xiaoyan Sun**, Hefei (CN)

(73) Assignees: **Anhui Huami Information Technology Co., Ltd.**, Anhui FTZ (CN); **Zepp, Inc.**, Cupertino, CA (US)

(**) Term: **15 Years**

(21) Appl. No.: **35/515,240**

(22) Filed: **Jul. 29, 2022**

(80) **Hague Agreement Data**

Int. Filing Date: **Jul. 29, 2022**

Int. Reg. No.: **DM/223098**

Int. Reg. Date: **Jul. 29, 2022**

Int. Reg. Pub. Date: **Sep. 30, 2022**

(51) **LOC (14) Cl.** **10-02**

(52) **U.S. Cl.**

USPC **D10/38**; D14/344

(57) **CLAIM**

The ornamental design for a watch, as shown and described.

DESCRIPTION

3. Watch

3.1 is a front view of a watch showing my design;
3.2 is a back view thereof;
3.3 is a left view thereof;
3.4 is a right view thereof;
3.5 is a top view thereof;
3.6 is a bottom view thereof;
3.7 is a perspective view thereof;
3.8 is another perspective view thereof; and
3.9 is a perspective view thereof, shown in a buckled state. The broken lines show portions of the watch that form no part of the claimed design. The shade lines in the figures show contour, not surface ornamentation, and form no part of the claimed design.

1 Claim, 9 Drawing Sheets
